UNITED STATES PATENT OFFICE.

JAMES S. FREER, OF RUTHERFORD, NEW JERSEY.

METHOD AND APPARATUS FOR PREPARING PHOTOENGRAVING-PLATES.

1,373,658.

Specification of Letters Patent.

Patented Apr. 5, 1921.

Application filed March 23, 1920. Serial No. 368,079.

To all whom it may concern:

Be it known that I, JAMES S. FREER, a citizen of the United States, and resident of Rutherford, in the county of Bergen and State of New Jersey, have invented certain new and useful Improvements in Methods and Apparatus for Preparing Photoengraving-Plates, of which the following is a specification.

- 10 My invention relates to improvements in the process and apparatus employed in etching, and is especially adapted for use in connection with the photoengraving and allied processes.
- 15 A great variety of processes for preparing and etching metal plates are known, all of which include the application to one side of a plate of an erosive-resisting coating. In a great many of these processes, it is necessary to heat the coating after it has been applied to the plate to render it tacky, to bake or burn it in, to melt it, or to accomplish various other results according to the requirements of the particular process. According to the uniform practice which is now followed the coating is heated to the necessary extent by placing the plate over or on a suitable stove or heater, the heat being transmitted through the plate to the coating.
- 20 After the coating or "resist" has been heated to a suitable point it is necessary to cool the plate before the process can be continued either by permitting the plate to cool slowly in the open air, or by subjecting it to various cooling processes, usually including the application of water. Two common methods employed in photoengraving include placing the hot plate under a stream of water or, in the improved method, passing
- 25 the plate over a roller covered with carpet saturated with water. These and other rapid cooling methods are objectionable because they tend to buckle or warp the plate, and when water is used directly, it must be removed from the plate before the next step in the process can be taken. Furthermore, sudden cooling tends to draw the temper of copper plates, materially reducing their usefulness. On the other hand, the slow cooling
- 30 of plates wastes a great deal of valuable time; and owing to the highly paid labor

and the nature of the work, the saving of time in the various etching processes is of the utmost importance.

This evil is particularly present in the process of treating line photoengraving plates generally employed in the United States, and sometimes referred to as the dragon's blood process. According to the usual practice in carrying out this process, the plate, after exposure and rolling up, is treated a number of times with a finely powdered resinous substance such as dragon's blood. This substance when melted has a strong affinity for the ink, and permeates the ink-bearing emulsion, forming, when cooled, an acid-resisting substance which is generally referred to as the resist.

In the process of etching by the dragon's blood method the plate is ordinarily immersed in the acid bath a number of times, three or four being customary; and before each insertion in the bath, or "bite", the plate is treated with the dragon's blood powder, ordinarily by the method known as "powdering four ways". This method consists in applying the powder to the plate four or more successive times, and brushing it across the surface of the plate each time in a different direction, it being customary to apply the powder from left to right, from right to left, from bottom to top, and from top to bottom. After each application of the powder in a single direction, the plate is heated so that the powder will melt against the sides of the lines in the direction in which it is brushed, and the plate is then cooled to a working temperature. Consequently, four separate heating and cooling steps are necessary between succeeding bites, and in addition a preliminary application of the dragon's blood to the entire plate after it has been rolled up is usual. After powdering four ways it will be apparent that each line along which etching is to take place will be accurately defined, as the side walls of the resist adjacent the line will be uniformly coated with the dragon's blood. It will be evident that under the general practice as described, a single plate is often heated and cooled as many as seventeen times. Consequently a large proportion of

the time required for this process is consumed in heating and cooling the plates, especially since each plate, if it is chilled by the application of water in the usual way, must again be reheated to a point where the ink is tacky and adapted to take up the dragon's blood.

According to the method universally employed in heating the plate in carrying out this process, the plate is held in a pair of tongs over an open gas stove, the plate body being heated first and imparting heat to the resist until the dragon's blood is melted. The plate is then cooled by any of the methods above indicated, either rapidly or slowly, although under modern conditions the rapid cooling is the almost universal practice. Warped and distorted plates necessarily result, and the time of the workman is taken up in swabbing off the water on the face of the plate and in reheating the plate to the proper temperature if necessary.

The primary object of my invention is to avoid the detrimental effects produced by the present practice of heating and cooling the body of the plate. By avoiding this practice, I insure the preservation of a normal flat condition of the plate and reduce very materially the total time required to carry out the usual photoengraving process or other processes of the general nature above indicated.

My invention in its broad aspect consists in the accomplishment of this object by the application of heat directly to the resist, as distinguished from application of the heat to the metal plate and the transmission of such heat from the plate to the resist. By this method it is possible to maintain the metal plate at practically normal temperature, as suitable means can readily be applied to the back of the plate for keeping it cool. Furthermore, in photoengraving the resinous powder such as dragon's blood melts at a relatively low temperature, ordinarily from 250° to 300° F., and the powder can be melted by the application of heat directly thereto and the plate withdrawn from proximity to the heater long before the temperature of the metal plate body has been raised to any substantial extent.

While this object may be accomplished by exposing the entire plate and resist to an even heat, as in an oven, where the dragon's blood on the surface will melt long before the plate reaches an equal temperature, I prefer to apply the heat only to the resist carrying surface of the plate, leaving the bottom of the plate protected or free from the heat. With this arrangement, the temperature of the plate will not be raised appreciably, and it will be ready for the next step of the process, such as powdering or

a bite, almost immediately upon withdrawal from the heating apparatus. Consequently, a very large part of the time necessary in properly etching a plate is eliminated, a feature of the greatest value commercially.

Obviously, this method of heating may be accomplished in a great variety of ways, and my invention is not restricted in its broad aspect to any particular method of applying the heat directly to the upper surface of the plate. However, there are in general two types of heating apparatus with which my method may advantageously be practised. Examples of these types are found in the accompanying drawings, in which—

Figure 1 is a perspective view of a heating oven, part of the door being broken away, and

Fig. 2 is a perspective view of another form of heating apparatus, a portion of the front being broken away.

The type of apparatus illustrated in Fig. 1 is adapted to supply heat to all sides of the plate, and preferably can be adjusted so that an even predetermined heat may be employed. Heaters of the oven type are especially suitable for this purpose, the form illustrated including an oven body 11 which may be made of sheet metal, having the usual door 12 and preferably a thermometer 13 to permit the etcher to regulate accurately the heat applied. If desired, suitable transparent windows may be provided to permit the observation of the plates while being heated. Any suitable type of heating element, such as gas burner 14, may be employed and when the heater is located within the body 11 it preferably is provided with a baffle plate 15 located thereabove to prevent uneven application of heat to the plates. Suitable plate supports, such as grates 16, are mounted in the oven body 11, and are preferably so constructed that the heated air from burner 14 may pass upwardly around the supports onto the top or resist-carrying portion of plates located on the supports. I also prefer to mount on grates 16 a suitable insulating or heat-resisting substance, such as sheets 17, which may be of asbestos or other material and may be laid on, connected to, or a permanent part of the supports 16. It will be apparent that with this arrangement the oven may be maintained at a temperature suitable for heating the resist, the temperature being very readily regulated by observation of thermometer 18, and corresponding manipulation of the heat supply.

In carrying out my process with this apparatus plates 18 are placed on the asbestos sheets 17 and door 12 is closed. In a short time, the dragon's blood or other part of

- the resist to be heated will be raised to the proper temperature, while the plates, insulated by sheets 17 upon which they rest, will rise in temperature very slowly, as most of 5 the heat must be transmitted to the plates through the resist. Consequently, when the resist has been suitably heated and the plates are removed, the temperature of the latter will be so low that very little or no cooling 10 is required, the ordinary chilling process being entirely unnecessary and the plate being ready almost immediately for the next operation.

It will be apparent that many variations 15 are possible in the oven type of heater, and I do not consider myself as restricted to any specific form of heat-producing apparatus, nor to the specific construction and arrangement of the plate supports or the oven body. 20 Obviously, heated air from an outside source may be introduced to equal advantage.

A second type of apparatus by which my invention may be carried out consists of 25 means for applying heat directly to the resist-carrying surface of the plate only, the plate preferably being supported in the open air. A great many devices, including various burners, electric heating coils 30 and the like are suitable. These heating elements may be mounted in any desired way, so that the plates may be placed adjacent thereto with the resist portions near the burners, or if desired, the heating elements 35 may be movable into position over a suitably located plate. One convenient illustration of the former arrangement is shown in Fig. 2, in which a hot plate 20 is mounted above and adjacent to a suitable 40 plate support, such as grill 21, the plate and grill being mounted on suitable supports, such as legs 22. Any preferred form of heating unit may be employed to maintain hot plate 20 at a suitable temperature, the 45 form illustrated including a common type of gas burner 23, which preferably is enclosed in a housing 24 over hot plate 20, to direct the heat downwardly against the plate. With this arrangement, the plate 50 carrying the resist may be placed on grill 21 beneath hot plate 20, exposing the resist to the heat, while the plate itself is only heated through the resist, and consequently 55 will rise in temperature very slowly. The operator is free to observe the action of the heat upon the resist, and can withdraw the plate as soon as the operation is completed, leaving the plate ready for the next step without any delay for cooling.

60 While I have described and shown a hot plate construction in Fig. 2 it will be evident that various forms of open burners may be used with equal facility. Furthermore, while I have shown the plate as lo-

cated below the burner, this position may be reversed if the resist contains no necessary material which will fall off when the plate is inverted.

Moreover, while I have described my invention primarily in its application to line 70 photoengraving to which it is particularly adapted, it is to be understood that I do not consider my invention to be limited to this process, as it may be applied to the very large number of processes of various 75 types generally referred to as "etching processes", which require the application of heat to the resist. Nor is my invention limited to processes of this nature wherein a resist material is melted, as it may likewise be used where the resist is burned in, as in halftone work, or where heating of the resist is required for any other purpose. My invention is also advantageous even where 80 a surface of the metal adjacent to the resist must be heated therewith, as by the application of heat to the resist, the surface of the metal adjacent thereto can be heated to the proper temperature while the remainder of the metal, either through radiation or by application of a cooling medium to the back of the plate, maintains a lower 85 temperature. The temperature to which the heating devices disclosed herein, or other devices of a similar nature, must be heated 90 in carrying out my process has not been stated, as such temperature need not be confined to any particular range. Under the present practice the operator trusts to observation to determine when the resist has 95 been heated to the proper point; and the same practice may be followed in employing the apparatus herein shown, though obviously the temperature may be regulated with much greater accuracy, and the time of the exposure of the resist to heat can consequently be gaged with greater precision. While I have indicated the scope of my invention and have described several specific 100 methods of applying it practically to well known processes, it will be apparent that many variations both in its application and in the exact type of apparatus employed can be made without departing from my invention, as set forth in this specification.

110 I claim:

1. In a process of etching metal plates by applying an erosive to a plate surface having selected portions covered with an erosive resisting coating and which includes 120 the heating of such coating, the step which consists in applying heat directly to the outer surface of the coating for a restricted period of time, sufficient to heat the coating and insufficient to considerably heat the body 125 of the plate.

2. In a process of etching metal plates by applying an erosive to a plate surface having

selected portions covered with an erosive resisting coating and which includes the heating of such coating, the step which consists in applying heat to the coated plate only on the plate face which carries the coating for a limited time, sufficient to heat the coating without considerably heating the plate.

3. In the process of photoengraving on metal plates by applying an erosive to a 10 resist carrying plate, and which includes the heating of such resist, the steps which consist in applying heat directly to the outer surface of the resist for a brief time, sufficient to properly heat the resist, and then 15 discontinuing the heating before the plate body becomes considerably heated, to avoid warping the plate and loss of time in cooling.

4. In the process of line photoengraving on metal plates in which selected portions of 20 a plate surface are covered with a suitable coating, a powdered resinous substance being applied to the coating and heated so that such substance will melt and adhere to the coating, forming a resist, the step which consists in melting the resinous substance by 25 applying heat directly to the outer surface of the coating carrying such substance for a limited time, sufficient to properly heat the surface materials without greatly raising the temperature of the body of the plate.

5. In the process of line photoengraving on metal plates in which selected portions of a plate surface are covered with a suitable coating, a powdered resinous substance being applied to the coating and heated so that such substance will melt and adhere to the coating, forming a resist, the step which con- 30

sists in melting the resinous substance by applying heat briefly to the coated plate only on the plate face which carries the coating, including the resinous substance, the application of heat being discontinued before the plate is greatly heated, avoiding warping and difficulties incident to cooling.

6. In a process of etching metal plates 45 which includes melting by heat a substance applied to the upper surface of the plate, the step consisting in applying heat only near the upper surface of the plate for a time only sufficient to melt said substance and insufficient to considerably heat the body of the plate, so that delays and warping due to plate-heating and cooling are substantially avoided.

7. In a process of etching metal plates 55 which includes heating material applied to the upper surface of the plate, the step consisting in heating the upper surface of the plate for a limited time, and protecting the body of the plate from considerable heat, to 60 avoid delay and warping.

8. In a process of etching metal plates which includes heating material applied to the upper surface of the plate, the step consisting in heating the upper surface of the 65 plate for a limited time, and protecting the under surface of the plate from heat, so that the body of the plate is not considerably heated, and warpage and delay for cooling are avoided.

Signed at New York city, in the county of New York and State of New York, this 20th day of March A. D. 1920.

JAMES S. FREER.
